UNITED STATES PATENT OFFICE

102,445

DESIGN FOR A COMBINED WASHING MACHINE AND WRINGER

Hazel P. Rodman, Alliance, Ohio, assignor to The
Alliance Porcelain Products Company, Alli-
ance, Ohio, a corporation of Ohio

Application July 14, 1936, Serial No. 63,837

Term of patent 14 years

To all whom it may concern:

Be it known that I, Hazel P. Rodman, a citizen
of the United States, residing at Alliance, county
of Stark and State of Ohio, have invented a cer-
tain new, original, and ornamental Design for
a Combined Washing Machine and Wringer, of
which the following is a specification, reference
being had to the accompanying drawing, forming
a part thereof.

Fig. 1 is a side elevational view of a combined

washing machine and wringer showing my new
design; and

Fig. 2 is a view partly in plan and partly in sec-
tion along the line II—II of Fig. 2.

The reverse side of the apparatus is similar in
appearance to the side shown.

I claim:

The ornamental design for a combined washing
machine and wringer as shown and described.

HAZEL P. RODMAN.
